UNITED STATES PATENT OFFICE.

CARL F. HADERER, OF WEST ALLIS, WISCONSIN, ASSIGNOR TO ALLIS-CHALMERS
MANUFACTURING COMPANY, OF MILWAUKEE, WISCONSIN, A CORPORATION
OF DELAWARE.

TILLER.

1,309,801.

Specification of Letters Patent. Patented July 15, 1919.

Application filed November 9, 1917. Serial No. 201,692.

To all whom it may concern:

Be it known that I, CARL F. HADERER, a subject of the Emperor of Germany, but having declared his intention of becoming a citizen of the United States, residing at West Allis, in the county of Milwaukee and State of Wisconsin, have invented the new and useful Tiller of which the following is a specification.

10 This invention relates to improvements in the construction of agricultural appliances and has specific relation to improvements in rotary soil-tilling machines.

An object of the invention is to provide 15 a soil tiller which is simple in construction and efficient in operation. One of the more specific objects is to provide an improved form of disintegrating element for rotary tillers. Another specific object is to provide 20 simple and efficient means for resiliently and detachably connecting the disintegrating elements to a carrier.

It has heretofore been proposed to construct a rotary tiller of a plurality of flexible 25 wire hooks secured to a rotating drum and adapted for angular displacement relatively to the drum around the axis of rotation. With this prior device, if a stone or similar obstruction was encountered by one of the 30 hooks, the obstructed hook would swing inwardly toward and around the axis of rotation, thereby permitting the rotor to pass over the obstruction. It has been found, however, that in order to provide sufficient 35 stiffness in these wire hooks to effectively till the soil, the hooks must be made of relatively heavy wire which will not readily submit to distortion by obstructions and which will often break rather than bend.

40 In order to overcome these difficulties of the prior devices, the present invention contemplates provision of a disintegrating element which in order to provide sufficient rigidity for tilling, is fixed against angular displacement around the rotor axis and relatively to 45 its carrier, but which will automatically move along the rotor axis and avoid injury to the rotor, in case an obstruction is encountered. With the present invention the 50 disintegrating elements are pivoted in planes perpendicular to the rotor axis and are automatically maintained in or returned after displacement, to such planes.

A clear conception of an embodiment of

the invention may be had by referring to 55 the drawing accompanying and forming a part of this specification in which like reference characters designate the same or similar parts in the various views.

Figure 1 is a side elevation of a rotary 60 tiller having one of the rear driving wheels omitted therefrom in order to more clearly disclose other details of construction.

Fig. 2 is an enlarged side elevation of a 65 set of three disintegrating hooks secured to a rotary carrier.

Fig. 3 is an enlarged top elevation of a 70 cam bracket adapted to center an adjacent hook and to automatically return the hook to normal after displacement thereof.

Fig. 4 is an enlarged end elevation of the 75 cam bracket shown in Fig. 3.

The tractor which impels the rotary tiller 80 device comprises a main frame 2 supported by a pair of rear traction wheels and a front steering wheel 4. The rear traction wheels 6 are propelled by means of an engine 3 of usual construction through the usual transmission gearing. The front steering wheel is manipulable by means of 85 a hand control 5. Secured to the rear end of the frame 2 is a rotor controlling and driving mechanism 7 which supports and forms a power transmission means for the tilling mechanism.

The mechanism 7 and the associated tilling 90 mechanism, may be raised by means of motor operated lifting mechanism which is mounted on the rear of the main frame 2 and is controllable from the driver's seat.

The tilling mechanism comprises a carrier 95 drivingly connected to a main drive shaft 9 and having mounted thereon a plurality of disintegrating elements. Each of the disintegrating elements comprises a spring arm 10, a head 11 locked to the spring arm by means of a cross pin 17, and a renewable point 12 fitting a tapered hole in the head 11. The inner extremities of the spring arm 10 are bent to form pivots which engage 100 openings 21 in brackets 13, 14 respectively. The brackets 13, 14 are detachably secured to the carrier 8 by means of cap screws.

Each of the rear brackets 13 is provided 105 with a pair of warped or cam surfaces 18 which extend laterally away from a rectilinear centering recess 19, see Figs. 3 and 4. The centering recess 19 lies in the plane

of the corresponding pivot openings 21 and has a surface which engages the adjacent spring arm 10 and normally retains the same in a plane perpendicular to the rotor axis. 5 The brackets 13, 14 of each set are spaced at such distances apart and around the rotor axis, that the spring arm 10 coacting therewith is under considerable tension whereby the arm 10 is prevented from moving out of 10 central or mid position unless lateral pressure is exerted against the outer extremity thereof. By exerting lateral pressure against the spring arm 10 the same may be moved out of its normal central plane to a position 15 such as indicated by dot and dash lines in Figs. 3 and 4. During this lateral movement of the arm 10 the portion thereof which normally rests in the recess 19, rides upon one of the cam surfaces 18 and partially withdraws the adjacent bent end of 20 the arm from its pivot opening 21 as indicated in Fig. 4, thereby augmenting the tension in the arm 10. Upon releasing the lateral pressure upon the arm, the tension 25 therein assisted by centrifugal force, causes the arm 10 to automatically ride back over the adjacent cam surface 18 and to reassume its normal mid position. By providing double cam surfaces 18, the disintegrating elements will be automatically returned to central position upon lateral displacement thereof in either direction. 30

During the normal operation of the tiller the tractor which impels the rotor is advanced by means of the engine 3, the direction of motion being controlled by means of the hand control 5. Operation of the tiller rotor is controlled by means of levers 27 which control the raising and lowering of 35 the rotor as well as the rotation thereof. The depth of tilling is controlled by means of a gage 15 associated with the tiller rotor, and the deflector 16 prevents material from being thrown upon the tractor. While till- 40 ing, the rotor revolves in a clockwise direction as viewed in Figs. 1 and 2, the points 12 being driven through the soil at a relatively high rate of speed and thoroughly disintegrating the same. 45

50 If, while tilling the soil, a stone or similar obstruction is encountered by one of the points 12, the corresponding disintegrating element will be moved laterally by virtue of the side thrust induced by the lateral component of the resisting force. It has been found that in a great majority of the cases where an obstruction is encountered, such obstruction does produce a lateral component of force which will tend to move the 55 disintegrating element laterally. The lateral motion of the obstructed disintegrating element will continue until this element is 60 able to clear the obstruction, whereupon the disintegrating element passes the obstruction and eventually automatically returns to 65

its normal or mid position. If the obstruction will not produce lateral motion of the obstructed disintegrating element, the entire rotor will be lifted bodily over the obstruction by the obstructed centrally retained disintegrating element. 70

With the construction of detachable points 12 as disclosed, these points may be readily fitted into their holding heads 11 by casting these heads around the tapered shanks of 75 the points. The points may be readily removed by striking the small rear ends thereof, so that replacement thereof is readily effected. The spring arms 10 may be readily removed either by prying the bent 80 ends thereof out of the openings 21 or by removing the bolts which normally retain in place the brackets 13, 14. The bolt holes of these brackets may be made slightly larger than the corresponding bolts in order 85 to permit some degree of adjustment so as to vary the tension of the corresponding spring arms. 90

It should be understood that it is not desired to be limited to the exact details herein shown and described, for obvious modifications within the scope of the appended claims may occur to a person skilled in the art. 95

It is claimed and desired to secure by Letters Patent:

1. As an article of manufacture, a disintegrating element comprising a bifurcated arm having a socket associated therewith, and a disintegrating tool frictionally held 100 within said socket and lying in the plane of the bifurcations of said arm.

2. As an article of manufacture, a disintegrating element comprising a bifurcated spring arm having a tapered socket associated therewith, and a disintegrating tool having a tapered shank coacting with said socket and lying in the plane of the bifurcations of said arm. 105

3. As an article of manufacture, a disintegrating element comprising a bifurcated spring arm having the ends of the bifurcations bent into alignment with each other to form pivots, and a disintegrating tool associated with said arm and lying in the plane 110 of said pivots.

4. In a tiller, a carrier having an axis, a bifurcated spring arm associated with said carrier and revoluble about said axis, means for stressing the bifurcations of said arm 115 by relative motion in the plane thereof upon shifting said arm along said axis, and a disintegrating tool associated with said arm. 120

5. In a tiller, a carrier having an axis, a bifurcated spring arm revoluble about said 125 axis, the ends of the arm bifurcations being associated with said carrier to prevent rearward displacement of said arm about said axis relatively to said carrier, means for stressing said bifurcations by relative mo- 130

tion in the plane thereof upon shifting of said arm along said axis, and a disintegrating tool associated with said arm.

6. In a tiller, a carrier having an axis, a bifurcated spring arm revoluble about said axis, the ends of the arm bifurcations being bent into alinement with each other, means connecting said bent ends to said carrier to prevent rearward displacement of said arm about said axis relatively to said carrier, means for stressing said bifurcations by relative motion in the plane thereof upon shifting of said arm along said axis, and a disintegrating tool associated with said arm.

15 7. In a tiller, a carrier having an axis, a

bifurcated spring arm revoluble about said axis, the ends of the arm bifurcations being bent into alinement with each other, means connecting said bent ends to said carrier to prevent rearward displacement of said arm 20 about said axis relatively to said carrier, means comprising an element having a cam surface engageable with a bifurcation of said arm to stress said bifurcations by relative motion in the plane thereof upon shifting of said arm about said bent ends, and a disintegrating tool associated with said arm. 25

In testimony whereof, the signature of the inventor is affixed hereto.

CARL F. HADERER.
